H. F. KELLNER

JETTY

Filed Jan. 10, 1924

INVENTOR.

Henry F. Kellner
BY
Warren D. House,
His ATTORNEY.

witness:

R. Hamilton

UNITED STATES PATENT OFFICE.

HENRY F. KELLNER, OF SILVER LAKE, KANSAS.

JETTY.

Application filed January 10, 1924. Serial No. 685,358.

My invention relates to improvements in jetties.

It relates particularly to and is an improvement upon the individual jetty units shown and described in two patents granted to me October 8, 1918, numbered 1,281,021, and 1,281,022. In the jetty units shown in said patents, each unit comprised crossed bars having flexible strands or bracing members connecting said bars adjacent to the ends thereof.

One of the objects of this invention is to provide a jetty unit of the kind described with novel means for holding the connecting bracing members from longitudinal slippage with respect to the bars.

A further object of my invention is to provide a jetty unit of the kind described which is simple, cheap to make, durable, strong, not liable to get out of order, one in which the parts may be easily and quickly assembled, and which is efficient in operation.

A further object of my invention is the provision of novel means for securely fastening a flexible member, such as a wire or a cable to a metal bar so as to hold the member from lengthwise slipping, without twisting it around the bar and without the use of accessory securing devices.

The novel features of my invention are hereinafter fully described and claimed.

In the accompanying drawing, which illustrates the preferred embodiment of my invention,

Fig. 1 is a perspective view of my improved jetty unit.

Fig. 2 is a top view thereof.

Fig. 3 is a cross section on the line 3—3 of Fig. 4,

Fig. 4 is an enlarged elevation of a portion of one of the crossed bars, and a sectional view on the line 4—4 of Fig. 3 of portions of two of the flexible members engaging said bar.

Similar reference characters designate similar parts in the different views.

1 and 2 designate two crossed angle bars fastened together at their place of intersection by a single bolt 3, and disposed at right angles to each other.

4 designates a third angle bar disposed at right angles to the bars 1 and 2 and fast-

ened to the bar 2 at the place of intersection with said bar by a single bolt 5, Fig. 2.

Each of the bars 1, 2 and 4, has each of its flanges provided at each side of its place of intersection with the other bars with a laterally off-set tongue 6 cut from the longitudinal edge of the flange near the adjacent end thereof, the tongue extending laterally outwardly from the flange and then parallel with the flange and spaced apart therefrom.

7, 8 and 9 designate three flexible bracing members, preferably three wires formed into three loops, each loop being disposed substantially in a plane at right angles to the planes of the other two loops.

The flexible bracing member 7 is extended between the tongues 6 of the bars 1 and 2 and the bodies of said bars at right angles to the edges of the tongues and adjacent edges of the bars respectively.

The ends of the bracing member 7 are twisted together at 10.

The flexible bracing member 8 in like manner engages the other two tongues of the other flange of each of the bars 4 and 2, the ends of the member 8 being twisted together at 11.

The flexible bracing member 9 engages the tongues 6 of the other flange of each of the members 4 and 1, the ends of the member 9 being twisted together at 12.

As is best shown in Figs. 3 and 4, each of the flexible bracing members is provided between each tongue 6 which it engages and the adjacent bar with two points of contact between which the flexible member is provided with a reverse bend 13, which holds the flexible member from longitudinal slippage. The flexible bracing members thus securely hold the bars in their proper position, when only one bolt is used to fasten together any two of the bars.

By having the flexible bracing members disposed at right angles to and between the adjacent edges of the tongues 6 and the bars, a very strong structure is afforded and the flexible members are gripped very tightly.

To one end of one of the bars, such as the bar 4, may be fastened in any suitable manner a metal ring 14, to which may be attached an anchoring cable, not shown.

I do not limit my invention to the structure shown and described, as many modifications, within the scope of the appended claims, may be made without departing from the spirit of my invention.

What I claim is:—

1. In a jetty, a jetty unit comprising two crossed bars fastened together at their place of intersection, and a flexible bracing member engaging each of said bars at opposite sides of said place of intersection, each of said bars having at the place of its engagement with said flexible bracing member two points of contact with said member, the latter being reversely bent between said points, whereby said member is held from longitudinal slippage.
2. In a jetty, a jetty unit comprising crossed bars fastened together at their place of intersection, each bar having at each side of said place of intersection a laterally off-set tongue cut from one edge of the bar, and a flexible bracing member extended between and at right angles to the adjacent edges of each tongue and the body of each bar and having a bend between said tongue and body.
3. In a jetty, a jetty unit comprising three crossed bars, two of which are at right angles to each other, the third being at right angles to the other two, said bars being fastened together at their place of intersection, a flexible bracing member engaging each of two of said bars at opposite sides of said place of intersection, and a second flexible bracing member engaging the other bar and one of said two bars at opposite sides of said place of intersection, each of said bars having means for holding the flexible

member engaged by it from longitudinal 40 slippage.

4. In a jetty, a jetty unit comprising three crossed bars, each being at right angles to the other two, said bars being fastened together at their place of intersection, each bar having at each side of the place of intersection a laterally off-set tongue cut from one edge of the bar, the flexible bracing member extended between and at right angles to the adjacent edges of 45 each tongue and body of each of two of the bars and a second flexible bracing member extended between and at right angles to the adjacent edges of each tongue and body of the third bar and of one of the other two bars, each flexible member having a bend between each tongue and body of each bar engaged by it.

5. In a jetty, a jetty unit comprising three crossed angle bars, each being at right angles to the other two, said bars being fastened together at their place of intersection, each flange of each angle bar having at each side of the place of intersection a laterally off-set tongue cut from the edge of 60 the bar, and three flexible bracing members, each disposed substantially at right angles to the other two, and each flexible member being extended between and at right angles to the adjacent edges of two oppositely disposed tongues of each of two of the bars, 65 each flexible member having a bend between each tongue engaged by it and the bar from which said tongue is cut.

In testimony whereof I have signed my 70 name to this specification.

HENRY F. KELLNER.
